FIG. 20

DEVICE FOR COMPENSATING AUTOMATICALLY FOR VARIATIONS IN THE TENSION ON AND LENGTH OF CABLES IN APPLIANCES FOR TRANSFERRING LOADS BETWEEN TWO MOVING OBJECTS BY CABLES

The present invention relates to a device for compensating automatically for variations in the tension on and length of cables in appliances for transferring loads between two moving objects by cables.

Such a device will find a use in particular in appliances for transferring loads between two ships (or between a ship and a fixed station) by cables, in order to compensate for variations in the tension and length of cables due essentially to small divergences in speed and from parallel direction of two ships in motion, and to any rolling and pitching movements to which the ships may be subjected.

These cable-transfer appliances generally comprise a carrier cable, stretched between two ships, and on which there runs a carriage supporting the load, and a cable governing the outward and return movements of the carriage along the carrier cable.

It will be understood that it is desirable, in spite of relative movements between the two ships, to maintain substantially constant tension on the one hand on the carrier cable in order to prevent irregular movements of the load in the vertical plane, and on the other hand on the carriage-governor cables in order to be able to keep positive control of the operations of despatching the load from, and bringing it up to, both ships.

Constant tension is automatically maintained on the carrier cable and on the carriage-governor cables in the compensating device to which the present invention relates.

According to the invention, the automatic compensating device comprises winders disposed on the moving object carrying the cable-winches and each assigned to compensating for variations in the length of one of the cables, the winders being interconnected and subjected to the action of a common return force of constant value in the direction of applying tension to the cables.

The invention will be described hereinafter in greater detail with reference to the various forms of embodiment which are illustrated in more or less diagrammatic fashion in the appended drawing.

FIG. 1 is a diagram showing the principle of an appliance for carrying out transfers between two moving objects by cables;

FIGS. 2, 3 and 4 are diagrammatic views showing a device for carrying out compensation by running the cables through pulley-blocks, as applied respectively to each of the two opposite directions of transfer and to the general case of transfers in both directions;

FIGS. 5 and 6 are diagrammatic views showing two variants in the application of the constant tensioning force to the cables in a device for carrying out compensation by running the cables through pulley-blocks;

FIGS. 7, 8 and 9 are diagrammatic views showing a device for carrying out compensation by mechanically interconnecting the winches, as applied respectively to each of the two opposite directions of transfer and to the general case of transfers in both directions;

FIGS. 10 and 11 are principle diagrams similar to those of FIG. 1, and showing the variations in sag and tension on the cables in the course of a transfer;

FIG. 12 is an overall diagrammatic view, showing a method of interconnecting the winches of the operating cables, and auxiliary tensioners for taking up variations in the length of these cables as a function of the variations in sag of the three cables;

FIGS. 13 and 14 are partial views extracted from FIG. 12, and showing two variants in the interconnection of the winches of the operating cables;

FIG. 15 is a principle diagram similar to that of FIG. 1;

FIG. 16 is a diagrammatic view showing a repeater for the positions and movements of the load;

FIG. 17 is a diagrammatic view showing how the positions and movements of the load are posted in the repeater illustrated in FIG. 16;

FIG. 18 is an overall diagrammatic view showing a variant of embodiment of the interconnection of the winches by differentials;

FIGS. 19 and 20 are a principle diagram and an overall diagrammatic view respectively of a variant of embodiment according to which the carrier cable takes the form of one of the operating cables.

The principle diagram in FIG. 1 shows an appliance for carrying out transfers between two arrival stations A and B fitted up respectively on two ships spaced from one another by a distance E which may be variable, the said ships being liable to oscillate about two roll axes *a* and *b*, themselves moving in space.

15 A carrier cable *C*₁ constitutes the running track of a carriage 1 from which a load *P* is suspended. The cable *C*₁, which is secured at 2 to the station B, is linked to a winder *D*₁ in the station A. The carriage 1 is attached at 3 to two opposed operating cables *C*₂ and *C*₃ which are respectively linked to two winders *D*₂ and *D*₃ in the station A, the cable *C*₃ passing over two deflector pulleys 4 in the station B.

20 The movements and positions of the carriage 1, and consequently of the load *P*, depend at each instant on the relative movements between the stations A and B and on the tension on the cables *C*₁, *C*₂, *C*₃ determined by the winders *D*₁, *D*₂, *D*₃.

25 It is clear that the tension on the carrier cable *C*₁ must remain substantially constant in order to avoid irregular movements of the load *P* in the vertical plane; likewise, the tension on the operating cables *C*₂, *C*₃ must make it possible on the one hand to control the arrival and departure speeds of the carriage at both stations, and on the other hand to keep the carriage in its arrival positions with respect to both stations.

30 Compensation for variations in the length of the three cables and control of the tension thereon are carried out automatically in a first form of embodiment according to the invention by means of three cable-winders comprising pulley-blocks, as illustrated in FIGS. 2, 3 and 4.

35 In FIG. 2, there is a limitation to the case of transferring the load with control over the arrival of the load at B.

40 In the station A, the three cables *C*₁, *C*₂ and *C*₃, which pass over deflector pulleys 5 and tensioning pulleys 6 mounted on a yoke 7 from which a common weight *M* is suspended, are attached to three winches *T*₁, *T*₂ and *T*₃ respectively.

45 For the sake of clarity in the drawing, the two groups of pulleys 5 and 6 are illustrated as having separate spindles, but it goes without saying that in each group the pulleys may be mounted on a common spindle.

50 The three pulley-blocks give a constant sum of the tensions on the three cables, the sum of the tensions being equal to *M*/2. Pulley-blocks with a plurality of runs of cable may be provided, for example for the operating cables *C*₂ and *C*₃, in order to obtain a constant greater tension on the carrier cable *C*₁, the sum of the tensions remaining constant.

55 The speed at which the carriage 1 arrives at the station B is easily controllable. If it is assumed that the winches *T*₁, *T*₂ and *T*₃ are stationary, the carriage 1 follows the movements of the station B, since the variation in the length of the cables is compensated for by the pulley-blocks in the station A. Under these conditions, if the winch *T*₃ is caused to wind at a speed equal to the unwinding speed of the winch *T*₂, for example by means of a mechanical coupling between these two winches, this speed which is easily adjustable, constitutes the speed of arrival at the post B, whatever the direction and amplitude of relative movements between the two stations.

60 65 In FIG. 3, there is a limitation to the case of transferring the load with control over the arrival of the load at A.

65 In this case, the cable *C*₂ is directly attached to a winch *U*₂; the cable *C*₁ is attached to a winch *U*₁ after passing over a pulley-block pulley 6, while the cable *C*₃, which is attached to a winch *U*₃, undergoes double blocking by passing over its pulley 8, linked to the weight *M*, and over a fixed pulley 9, the sum of the tensions on the three cables being substantially constant.

70 75 The speed at which the carriage 1 arrives at the station A is likewise easily controllable. The three winches *U*₁, *U*₂, *U*₃

being stationary, the carriage 1 follows the movements of the station A; for any variation in the distance between the two stations the distances traversed by the cable C_3 will be twice as great as those traversed by the cable C_1 , the length of the cable C_2 being constant. Consequently, if the winch U_2 is caused to wind at a speed equal to the unwinding speed of the winch U_3 , the speed of arrival at the station A will be controlled, and will be that at which the cable C_2 is wound.

In the foregoing, only the control of arrivals at the stations A and B is described; it goes without saying that the load is controlled in its departure from both stations by the same means, simply by inverting the directions of winding and unwinding on the winches T_2 , T_3 (FIG. 2) or U_2 , U_3 (FIG. 1).

FIG. 4 applies to the more general case of bringing in and launching the carriage on its own or loaded, at both of the two stations.

As FIG. 4 shows, the station A comprises a pulley-block for the cables C_1 , C_2 , C_3 according to FIG. 2, made up of pulleys 6 and a weight M_1 , and a pulley-block for the cables C_1 and C_3 according to FIG. 3, made up of the pulleys 8, 9 and a weight M_2 , the cables C_1 and C_3 being guided between the two pulley-blocks by the deflector pulleys 10 and 11.

The two weights M_1 and M_2 are provided with brakes for locking to the respective guides m_1 and m_2 , braking being carried out, for example, by means of remote control by electromagnets, not illustrated.

Transfer of the load from the station A to the station B will proceed in the following manner:

At the start of launching the weight M_1 will be locked by its brake, the weight M_2 being free. Unwinding the cable C_1 by the winch U_2 and winding up the cable C_3 by the winch U_3 will launch the load at the unwinding speed of the cable C_2 . In order to bring the load up to the station B, the weight M_1 will be released and the weight M_2 will be locked before the load approaches the station B. Controlling the speeds of the winches U_2 and U_3 determines the speed at which the load arrives at the station B.

Transfer of the load from the station B to the station A will proceed in the same manner, the weight M_1 alone remaining released at the time of launching; before arrival at the station A, the weight M_1 will be locked and the weight M_2 released.

The operations of locking and releasing the two weights may be combined so as to take place in fully automatic fashion.

The pulley-blocks for the three cables in the station A may be of the type comprising multiple runs of cable, so as to limit the movements of the weights M_1 and M_2 , and to make the sums of the tensions on the cables different while these weights are of the same value.

Likewise, instead of using weights such as M in order to determine the tensions on the cables, recourse may be had to elastic return forces, exerted for example by a spring or by a pneumatic or oleopneumatic device; the return members M may be inserted either between the pulley-block yokes 7 and a fixed point 13 (FIG. 5), and work in tension, or between the pulley-block yokes 7 and a fixed yoke 7a supporting the fixed pulley-block pulleys 6a (FIG. 6), and work in compression.

In a second form of embodiment according to the invention, compensation for variations in the lengths of and tension on the cables is provided by means of three winders comprising mechanical differentials, as illustrated in FIGS. 7, 8 and 9.

In FIG. 7, there is a limitation to controlling the load in its arrival and launching at the station B (FIG. 1).

In the station A, the cable C_1 is attached to a winch t_1 driven by a reversible constant-torque motor F_1 ; the cables C_2 and C_3 are attached to two winches t_2 and t_3 respectively, each linked to one of the planetary gears q_1 of a differential Q whereof the other planetary gear q_2 is linked by a pinion q_3 to a pinion q_4 fast with the shaft of the winch t_1 .

The cages q_5 of the two differentials are linked respectively by gears e_2 and e_3 to the motors F_2 and F_3 .

The ratios between the diameter of the winch t_1 and the diameters of the winches t_2 , t_3 on the one hand, and between

the diameter of the pinion q_4 and the pinions q_3 on the other hand, are made such that when the motors F_2 and F_3 are stationary the winding and unwinding speeds of the cables C_1 , C_2 and C_3 are equal.

5 The relative speed of the load upon arriving at the station B is easily controllable. The motors F_2 and F_3 being stationary, they lock the cages q_5 of both differentials Q. The three cables are allowed to wind and unwind as a result of relative movements between the two stations, and the load follows the movements of the station B. The motors F_2 and F_3 being linked to one another by a mechanical or other coupling, not illustrated, the cable C_2 is caused to unwind at a speed equal to the winding speed of the cable C_3 , this speed being the desired speed of arrival or launching at the station B.

10 15 In FIG. 8, there is a limitation to controlling arrival and launching at the station A (FIG. 1).

The cable C_2 is attached to the winch u_2 , which is directly driven via the gears e_2 by the motor F_2 . The cable C_3 is attached to the winch u_3 , which is linked via the differential Q to the motor F_3 by the gears e_3 and to the pinion q_3 in mesh with the pinion q_4 , fast with the shaft of the winch u_1 . The ratio between the pinions q_3 and q_4 is chosen so that when the motors F_2 and F_3 are stationary the winding and unwinding speed 20 of the cable C_3 will be twice as great as the winding and unwinding speed of the cable C_1 . The load follows the movements of the station A; the speed of winding the cable C_2 and unwinding the cable C_3 by the two motors F_2 and F_3 coupled to one another will be the speed of arrival or launching at the station A.

25 FIG. 9 applies to the general case of arrivals and launchings at both stations by means of a particular combination of the devices comprising winches and differentials according to FIGS. 7 and 8.

30 35 The winch u_1 for winding the cable C_1 is linked by the pinion q_4 and the two pinions q_3 to the differential Q_2 of the winch u_2 and to the differential Q_3 of the winch u_3 . On the shafts of the planetary gears q_2 of the differentials Q_2 and Q_3 there are clutches p_2 and p_3 respectively, enabling these planetary gears to be disconnected from the corresponding pinions q_3 .

40 45 The shaft of the planetary gear q_2 of the differential Q_2 is furthermore equipped with a locking brake f_2 , while the shaft of the planetary gear q_2 of the differential Q_3 carries a pinion q_7 in mesh with a pinion q_8 keyed to a shaft q_9 which is linked by way of a clutch p_4 to the shaft of the winch u_1 . The ratio between the pinions q_7 and q_8 is half the ratio between the pinions q_3 and q_4 .

50 55 For arrivals and launchings at the station B, the brake f_2 is released, the clutches p_2 and p_3 are engaged, and the clutch p_4 is disengaged. The operation is then that described for the case of FIG. 7.

For arrivals and launchings at the station A, the brake f_2 is locked, the clutches p_2 , p_3 are disengaged, and the clutch p_4 is engaged. The operation is then that described for the case of FIG. 8.

60 65 The use of winders comprising mechanical differentials according to FIG. 7, 8 and 9 has the advantage of allowing for continuous variations, of any desired value, in the distance between the two moving objects while an operation of transferring a load from one moving object to the other is in progress.

70 75 The devices for compensating for variations in the lengths of cables which have just been described, comprising pulley-blocks for the cables or comprising differentials, may be completed in accordance with the invention by auxiliary members for compensating for variations in the lengths of and tensions on the operating cables due to the variable sag of the carrier cable under the action of the load being transferred.

Figs. 10 and 11 are views extracted from FIG. 1, showing respectively the load P in the vicinity of the station A and in the middle of the span between A and B.

It will be understood that the loop closed by the operating cables C_2 and C_3 will be larger in the case of FIG. 11 than in the case of FIG. 10. When the load P is displaced from A

towards the middle of the span, the cable C_2 retards the descent, and the tension on the cable C_3 must be sufficient to limit the free sag of this cable. Likewise, when the load P goes from the middle of the span towards the station B , the cable C_3 becomes the driving cable, and the tension on the cable C_2 must be sufficient to limit its sag. The tensions on the cables C_2 and C_3 may naturally reverse their directions as from any other position on the span, from the bottom point of the load, as a function of the differences in level between the two moving objects.

A reversing device, whereof different variants of embodiment are illustrated in FIGS. 12, 13 and 14, ensures that minimum tensions are maintained on the operating cables C_2 and C_3 not tensioned by the load. In these FIG., the members for compensating for cable-lengths have not been illustrated in detail for the sake of clarity in the drawing, and are designated by K .

As FIG. 12 shows, the two winches U_2 and U_3 for winding and unwinding the cables C_2 and C_3 , driven by two motors F_2 and F_3 , are linked to one another by a reversing gear N ; on the shaft of the winch U_2 (or of the winch U_3) there is a clutch S enabling the two winches to be disengaged. The cables C_2 and C_3 are equipped with auxiliary tensioners H_2 and H_3 of any type, calibrated to the desired minimum value of tension on these cables when they are not tensioned by the load.

Displacements of the tensioners H_2 , H_3 are limited by upper safety abutments h_2 , h_3 and lower safety abutments b_2 , b_3 .

When the clutch S is disengaged, the two winches can operate separately, which facilitates placing the cables C_2 and C_3 in position during preparation for a transfer operation.

The clutch S being engaged, and power being supplied to the two motors F_2 , F_3 in parallel, the winding and unwinding speeds of the two cables are the same.

When the load leaves the station A for the station B (FIG. 10), the cable C_2 is tensioned by the component of the load P greater than the tension imposed by the tensioner H_2 , and the latter is brought into contact with the upper abutment h_2 , the cable C_3 being tensioned only by the tensioner H_3 , which approaches its lower abutment b_3 . When the load approaches the bottom point of the span, the tension on the cable C_2 decreases, and as soon as it is lower than the tension defined by the tensioner H_2 the latter leaves its upper position h_2 . During this phase, the two motors F_2 and F_3 have been acting as holding brakes.

When the load P has passed the bottom point of the span, the cable C_3 becomes the driving cable. Under the action of the component of the load P , the tension on the cable C_3 exceeds the value imposed by the tensioner H_3 , which comes into contact with its upper abutment h_3 , while the tensioner H_2 of the cable C_2 drops towards its lower abutment b_2 and maintains the minimum tension provided for on this cable.

FIG. 13 is a partial view extracted from FIG. 12, showing a first variant of embodiment of the link between the two winches U_2 and U_3 .

Besides the clutch S on one of the shafts of the winches U_2 and U_3 , there are clutches S_2 and S_3 on the shafts linking these winches to their motors F_2 and F_3 . This arrangement is more particularly applicable in the case in which it is difficult to put the two motors in parallel.

When the clutch S is disengaged and the clutches S_2 and S_3 are engaged, the two winches are independent, and allow the cables C_2 and C_3 to be easily placed in position. The clutch S being engaged, and only one of the clutches S_2 and S_3 being engaged, only that motor which is not declutched from its winch drives the two winches for winding and unwinding the cables C_2 , C_3 .

FIG. 14 is likewise a partial view extracted from FIG. 12, showing a second variant of embodiment of the link between the two winches U_2 and U_3 .

The two winches, driven by the motors F_2 and F_3 , are linked to the planetary gears g_2 and g_3 of a differential C whereof the cage S_1 is equipped with a locking brake g_4 . According to whether the brake g_4 is released or applied, the two winches

can operate independently or, if the two motors are coupled in parallel, the said winches can unwind and wind the two cables simultaneously. This arrangement can exhibit the advantage with respect to arrangements using clutches that the combination of movements is controlled with respect to a fixed element belonging to the brake.

The different arrangements according to FIGS. 12, 13 and 14 may be used in compensating for variations in length of the cables by differentials according to FIGS 7, 8 and 9, the auxiliary tensioners H_2 and H_3 for the cables C_2 and C_3 being disposed where the cables enter the unit K containing the members for compensating for cablelengths at the station A ; the declutchable reversing mechanism is then inserted between the two motors F_2 and F_3 .

FIGS. 15, 16 and 17 relate to a repeater for the positions and movements of the load between the two moving objects.

The appliance for carrying out transfers between two moving objects A and B shown diagrammatically in FIG. 15 comprises a carrier cable C_1 on which there moves a carriage 1 supporting a load P , and two operating cables C_2 , C_3 attached in opposition at 3 to the carriage 1 .

On the moving object A , the three cables are attached to three winches U_1 , U_2 and U_3 respectively; the governor station 25 for the winches on the moving object A comprises, as described above, a device (K) for compensating for variations in length of the three cables due to relative movements of the two moving objects, a device (N) for interconnecting the two winches U_2 , U_3 of the operating cables C_2 , C_3 , and a device H 30 for compensating for sag in the cables. On the moving object B , the carrier cable C_1 is secured at 2 , and the operating cable C_3 is guided over two pulleys 4 .

The number of revolutions carried out by the winch U_1 in order to secure the cable to the moving object B gives an indication of the instantaneous distance E_1 between the two moving objects; likewise, the number of revolutions carried out by the winch U_2 while the carriage 1 is moving towards the moving object B gives an indication of the instantaneous distance E_2 between the station A and the load P . The distance is the image of the distance to be traversed by the load until it arrives at the moving object B .

The distance E_1 , and consequently the distance E_1-E_2 , being variable as a function of the relative movements of the two moving objects, it is necessary to know the instantaneous distance E_1-E_2 for the purpose of accurate and possibly automatic control of the speeds of arrival at the moving object B , knowledge of the distance E_2 being itself useful in controlling arrivals at the moving object A .

FIG. 16 shows one particular form of embodiment of a repeater according to the invention, enabling an indication to be given at any instant of the true distance to be traversed by the load before it arrives at one or other of the two moving objects.

The repeater illustrated is applicable to the case of compensation for variations in the lengths of the cables by means of a link via differentials between the winch of the carrier cable and the two winches of the operating cables (FIG. 9).

Only the link via a differential Q_2 between the winch U_1 of the carrier cable C_1 and the winch U_2 of the operating cable C_2 is illustrated, the cable C_2 being the cable which returns the load to the station A . The diameter of the winch U_1 is twice that of the winch U_2 .

The shaft of the winch U_1 is linked via a reversible reduction gear L_1 to the planetary gear v_1 of a differential V whereof the planetary gear v_2 is linked via a train of reduction gears L_2 to the shaft of the winch U_2 . The cage of the differential V carries a posting disc R_1 cooperating with a fixed pointer r_1 . A posting disc R_2 , cooperating with a fixed pointer r_2 , is centered on the shaft of the planetary gear v_2 so as to be capable of rotating on this shaft. This disc is driven via gearing L_3 at half the speed of the planetary gear v_2 . The reduction ratios in the gearings L_1 , L_2 and L_3 are so chosen that the angular movements of the discs R_1 and R_2 are equal for the same lengths of winding and 75 unwinding the cables C_1 and C_2 . A clutch P_2 enables the winch

U_2 to be disengaged from the winch U_1 for the purpose of preparing for a transfer operation.

Posting of the movements and positions of the load P with respect to the two moving objects is shown in FIG. 17.

The discs R_1 and R_2 bear scales in distances whereof the zeros are opposite to the pointers r_1 and r_2 when the cables are fully withdrawn by the winches U_1 and U_2 , that is to say before preparing for a transfer.

Before a transfer, the carrier cable C_1 is unwound, and the pointer r_1 indicates on the disc R_1 the length E_1 unwound, and also any variations which there may be in this length, the zero of the scale on this disc being at O_1 . The zero of the scale on the disc R_2 has remained opposite to the pointer r_2 .

When the load is launched towards the moving object B , the disc R_1 is driven in the reverse direction by the winch U_2 ; the load is arriving at the moving object B when the zero on the disc R_1 has returned opposite to the pointer r_1 , stoppage of the operation having been kept under control by observation of the decreasing angular displacement between the zero of the scale and the pointer r_1 . At the same time, the disc R_2 has rotated through the same angle and in the same direction as the disc R_1 , and the pointer r_2 indicates the instantaneous distance E_1 on the scale on the disc R_2 whereof the zero is then at O_2 .

For an operation in the opposite direction, displacement of the load is controlled while observing zero on the disc R_2 returning towards the pointer r_2 ; arrival corresponds to zero on this disc coming opposite to the pointer r_2 ; the pointer r_1 again indicates the instantaneous distance E_1 on the disc R_1 .

This method of posting is independent of the amplitude and duration of variations in the distance E_1 since every variation reacts instantaneously on the angular displacement of zero on the disc R_1 for transfers of the load to the moving object B , and on the angular displacement of zero on the disc R_2 for transfers in the opposite direction.

The repeater furthermore makes it possible to fix the start of deceleration of the load before it arrives at the two moving objects.

For this purpose, fixed or adjustable markers such as k_1 and k_2 are arranged on the disc R_1 and R_2 so as to be at definite angles such as a_1 and a_2 , which may or may not be equal, to the zeros of the scales on these discs.

The arrival of these markers opposite to the respective pointers r_1 and r_2 will indicate that the desired periods of deceleration should be started.

The repeater described above is applicable to a transfer device wherein compensation for variations in length of the cables is provided by pulley-blocks on the cables. In order to take into account the lengths of cable in the pulley-blocks, the positions of the pointers r_1 and r_2 may then be adjusted in order to bring them opposite to the zeros of the scales on the two discs.

Such a possibility of adjusting the positions of the pointers r_1 and r_2 furthermore enables account to be taken of slight variations in the length of the cable C_2 due to the compensator H for sag in the operating cables.

Instead of the provision of angular posting on discs such as R_1 and R_2 , the relative angular movements of the cage v_3 of the differential V and the angular movements of the disc R_2 may be transformed, for example by means of toothed racks, into rectilinear movements of the two scales with respect to the reading pointers.

Likewise, instead of posting by directly reading the relative positions of the disc R_1 and R_2 by means of the pointers r_1 and r_2 , these two discs may take the form of cams cooperating with angular-position detectors such as d_1 and d_2 of any type transmitting instruction pulses to a regulator R which groups the manual or automatic control members for the successive operations of launching, transfer and arrival.

FIG. 18 relates to a variant of embodiment making it possible to simplify the operations intended to make the appliance work under the conditions required for the operations of arrival at the two moving objects.

Management of the winches u_2 and u_3 of the operating cables C_2 and C_3 is as described above for the case in which compensation for variations in cable-lengths is carried out by means of differentials intended to apply to each of the two winches a definite fraction of a constant torque for tensioning the three cables which is applied to the winch of the carrier cable C_1 .

The winch u_2 of the operating cable C_2 , which acts in the direction of returning the load towards the moving object carrying the winches, is linked to the planetary gear q_1 of the differential Q_2 whereof the satellite-carrier cage q_5 is driven by the motor F_2 . Likewise, the winch of the operating cable C_3 , which acts in the direction of displacing the load towards the other moving object, is linked to the planetary gear q_1 of the differential Q_3 whereof the satellite-carrier cage q_5 is driven by the motor F_3 . Finally, the winch u_1 of the carrier cable C_1 is linked to a torque-motor F_1 which applies a constant torque to it.

10 The winch u_1 is linked to the satellite-carrier cage w_2 of a differential W by gearing w_1 whereof the step-up ratio is equal to the ratio between the diameter of the winch u_1 and the equal diameters of the winches u_2, u_3 . The planetary gear w_3 of this differential is linked on the one hand via a shaft w_4 to the 15 planetary gear q_2 of the differential Q_3 , and on the other hand by way of a clutch P_5 to a shaft w_5 linking the planetary gear w_6 of the differential W to the planetary gear q_2 of the differential Q_2 , this shaft being equipped with a locking brake f_2 . On the shaft w_4 there is a clutch w_7 enabling the differentials W and 20 Q_3 to be disengaged from one another.

25 The winch u_1 is linked to the satellite-carrier cage w_2 of a differential W by gearing w_1 whereof the step-up ratio is equal to the ratio between the diameter of the winch u_1 and the equal diameters of the winches u_2, u_3 . The planetary gear w_3 of this differential is linked on the one hand via a shaft w_4 to the planetary gear q_2 of the differential Q_3 , and on the other hand by way of a clutch P_5 to a shaft w_5 linking the planetary gear w_6 of the differential W to the planetary gear q_2 of the differential Q_2 , this shaft being equipped with a locking brake f_2 . On the shaft w_4 there is a clutch w_7 enabling the differentials W and 30 Q_3 to be disengaged from one another.

35 In order to place the carrier cable C_1 in position between the two moving objects, the brake F_2 is locked and the clutch w_7 is disengaged in order to enable the cage w_2 of the differential W , and consequently the winch u_1 of the carrier cable, to rotate freely. The winches u_2 and u_3 may be used separately in order to place the operating cables C_2 and C_3 in position and under tension.

When the carriage supporting the load has arrived at the moving object carrying the winches, the brake f_2 remaining 40 applied, the clutch P_5 being disengaged and the clutch w_7 being engaged, the cables C_1 and C_3 are allowed to vary in length, due to relative movements of the two moving objects, by the cable C_3 being unwound or wound up twice as much as the cable C_1 . At the time of launching the load by the cable C_2 being unwound and the cable C_3 being wound up by their respective winches u_2 and u_3 , the effects of variations in the length of the cables are cancelled out by play in the differentials W and Q_3 , the load moving at the speed regulated by the winches u_2 and u_3 . The same applies when the load is arriving 45 at the moving object under consideration.

50 In order to bring the load up to the opposite moving object, the clutch P_5 is engaged and the brake f_2 is released; the planetary gears w_3 and w_6 of the differential W then being fast with one another, the shafts w_4 and w_5 are driven in the same direction by any rotation which the cage w_2 of the differential W may carry out, and play in the differentials Q_2 and Q_3 allows the load to follow relative displacements of this moving object. The speed of arrival will therefore be that regulated by the 55 winches u_2 and u_3 . The same will apply to launching the load from this moving object.

60 The working conditions of the clutch P_5 and the brake f_2 for arrivals and launchings at both moving objects may be reversed with the load substantially half-way in both directions, without for that reason interrupting displacement of the load by the winches u_2 and u_3 .

65 This reversal may be carried out automatically by means subject to control for example by the winches u_1 and u_2 .

70 The arrangement described above thus enables loads to be brought up to each of the two moving objects simply by combined operation of the brake f_2 and the clutch P_5 , independently of variations in the length of and tension on the cables in the course of an operation.

75 FIGS. 19 and 20 relate to a variant of embodiment for a transfer appliance comprising two cables.

The diagram in FIG. 19 shows the two winches u_2 , u_3 of the two operating cables C_2 and C_3 attached in opposition at 3 to the load-carrier carriage 1 which runs on the cable C_3 .

The two winches u_2 and u_3 are carried by the moving object A, and the moving object B carries the deflector pulleys w_4 for the cable C_3 .

The winch u_2 is linked to the planetary gear q_1 of a differential Q_2 whereof the cage q_5 is driven by a motor F_2 by way of gearing L_2 and a nonreversible worm mechanism I_2 ; the winch u_3 is linked to the planetary gear q_1 of a differential Q_3 whereof cage q_5 is driven by a motor F_3 by way of gearing L_3 and a nonreversible worm mechanism I_3 .

The planetary gears q_2 of the differentials Q_2 and Q_3 are linked by shafts W_5 and W_4 respectively to the planetary gears w_6 and w_3 of a differential W whereof the cage is linked by gearing w_1 to a torque-motor F_1 .

The shaft w_5 is equipped with a brake f_2 and a clutch p_5 which enables it to be made fast with the shaft w_4 , itself equipped with a clutch w_7 .

The shafts n_2 and n_3 of the two worm mechanisms I_2 and I_3 are linked to one another by a reversing gear N_1 , the shaft n_2 being equipped with a clutch S_3 .

In order to place the cable C_3 in position between the two moving objects A and B, the clutch w_7 is disengaged and the brake f_2 is applied; as a result of play in the differential Q_3 , the winch u_3 , which is then free, allows the cable C_3 to unwind.

The load-carrier carriage being on the moving object A carrying the winches, the torque-motor F_1 applies tension to the cable C_3 by way of the winch u_3 , the clutch w_7 being engaged, the clutch P_5 being disengaged, and the brake f_2 remaining applied. Variations in the distance between the two moving objects will have the effect of causing the winch u_3 to wind up or unwind the cable C_3 to the extent of twice the variations in distance.

For operations of launching the load P by the moving object A, the two winches u_2 and u_3 are driven via the differentials Q_2 and Q_3 by the motors F_2 and F_3 interconnected by the clutch S_3 ; the distance between the load and the moving object A remains that governed by the winches, whatever the variation in distance between the two moving objects. The same applies as regards operations of bringing the load up to the moving object A.

Before operations of arrival at the moving object B, the brake f_2 is released and the clutch p_5 is engaged. The tensioning torque is then distributed to the two winches u_2 and u_3 by the differential W , and variations in the distance between the two moving objects have the effect of causing the two cables C_2 and C_3 to be simultaneously wound up and unwound to the same extent; the distance between the load and the moving object B remains that governed by the two winches. The same applies to operations of launching the load from the station B.

When the load-carrier carriage has arrived at the moving object A, disengagement of the clutches w_7 and S_3 enables the motor F_3 to rewind on to the winch u_3 the unwound length of the cable C_3 between the two moving objects.

If the winding capacity of the winch u_3 is made twice that of the winch u_2 , and if the winch u_3 is used for placing the cable C_3 in position between the two moving objects and for returning this cable to the moving object A, all the operations of a transfer may be carried out without any need for readjustments to windings on the two winches.

I claim:

1. Device for compensating automatically for variations in the tension and length of cables for transfer of loads between a moving sending ship and a moving receiving ship having a carrier cable extending between said ships, a trolley moving on said cable, said trolley carrying the load, an outhaul cable, an inhaul cable, said outhaul and said inhaul cables controlling the movements of said trolley respectively between said receiving and said sending ships, a winch for each of said cables, a motor for each of said winches for rotating the respec-

tive one of said winches in both directions, said winches for said inhaul and said outhaul cables being rotated in opposite directions and at equal speeds for control of the movement of the load and means for compensating for the length and tension on said cables, said winches, said motors, and said compensating means being mounted on said sending ship, said compensating means including a first mechanical control device for control of the position of said trolley with respect to said receiving ship controlling the winding in and the paying out of said carrier cable and of said inhaul and of said outhaul cables to lengths substantially equal to the changes of the distance between said stations, a second mechanical control device for control of the position of said trolley with respect to said sending ship controlling the winding in and the paying out of said carrier cable to a length substantially equal to the variations of the distance between said stations and to a double length of said outhaul cable, means for selectively blocking said control devices, each of said control devices including separate means for winding in and for paying out each of said cables controlled directly by the variations of the distance between said ships independently of the movement of said trolley, said winding in and said paying out means of each of said control devices being conjugated and subjected, in the directions of the tension on said cables, to a common constant value return force.

2. A device as described in claim 1, said control devices including a pulley for and receiving each of said cables and a constant cable-tension load on said pulleys.

3. Device as described in claim 1, said control devices including two differentials coupling said winch for said carrier cable to said winches for said operating cables, said differentials applying to each of said winches for said operating cables a definite fraction of a constant torque for tensioning said cables, said constant torque being applied to said carrier cable winch by a reversible torque motor.

4. A device as described in claim 3, said winches for said operating cables being interconnected by a reversing mechanism declutchable for individual movements of each of said operating cables.

5. Device as described in claim 3, including an auxiliary tensioner for each of said operating cables providing a minimum tension on the respective one of said operating cables when not under tension by the load during transfer, each of said auxiliary tensioners being disengaged by tension on the respective one of said operating cables.

6. A device as described in claim 3, said winches of said operating cables being each coupled to a differential, a satellite carrier cage for each of said differentials driven by the motor of the respective one of said winches, said differentials being coupled to a third differential, a satellite-carrier cage for said third differential coupled to said winch of said carrier cable, planetary gears for said first named differentials connected by a clutch, a locking brake for said planetary gear of said differential of said winch for said operating cable which moves the load toward said sending ship, said clutch and said brake being interconnected for selective operation at arrival of the load.

7. A device as described in claim 6, including a clutch disposed between said differential coupled to said carrier cable winch and said differential of said winch for said cable displacing the load away from said sending ship.

8. A device as described in claim 7, including a repeater for the positions and movements of the load, said carrier cable winch and said winch of said cable moving the load toward said sending ship being respectively coupled to two planetary gears of a differential, a cage for said last named differential, a scale actuated by said last named cage posting the instantaneous distance from the load to the receiving ship and a second scale actuated by the rotation of said operating cable winch posting the instantaneous distance from the load to the sending ship.

9. A device as described in claim 1, said control devices including a differential connected to each of two said winches, a satellite carrier cage for each of said differentials driven by the motor driving the respective one of said winches, a third dif-

ferential, said two differentials being connected to said third differential and a torque motor connected to said third differential applying a torque for tensioning said cables.
